UNITED STATES PATENT OFFICE.

LOUIS V. ARONSON, OF NEWARK, NEW JERSEY.

TOY GUN.

Application filed May 31, 1924. Serial No. 717,049.

The invention relates to toys, and has as an object the provision of a toy which will simulate a rifle and produce a shower of sparks when discharged.

5 A further object of the invention is the provision of a toy rifle which may be repeatedly discharged without reloading.

Further objects of the invention will appear from the following description when 10 read in connection with the accompanying drawings showing an illustrated embodiment of the invention, and in which:

Figure 1 is a central vertical section with the stock broken away;

15 Fig. 2 is a detail vertical section similar to Figure 1, showing the device ready for discharge;

Figs. 3, 4 and 5 are vertical transverse sections on the lines 3—3; 4—4 and 5—5, respectively, of Figure 1; and

20 Fig. 6 is a plan view of the blank from which the sparking element holder may be formed.

As shown, the device is provided with a 25 stock member 10, notched at 11 for co-action with a sliding hammer member or button 12 and having a slot there-through at 13 for the passage of a trigger 14.

A trigger guard is shown at 15 formed of 30 an U-shaped wire or rod having ends 16—17 projecting into openings in the stock.

A barrel 18, preferably formed of tubular sheet metal is provided, and may be formed by bending a flat strip of metal to provide 35 a joint at 19 along the lower side of the barrel. To secure the barrel to the stock, wings 20, 21 may be provided by deflecting portions of the material of the barrel 18 into downwardly extending parallel positions, which receive the fore-hand portion 40 of the stock 10 between them and to which they may be secured by brads 22.

To provide sparks when the device is operated, there is shown a piece of pyrophoric 45 material 23 housed in a cylindrical receptacle 24 mounted upon the barrel adjacent its front end. The receptacle with means for pivoting the pressing lever 25 may be formed from a blank such as shown in Fig. 50 6, which is doubled upon itself so that the portion 26 may form a tubular receptacle 24, and the part thus produced may be soldered or otherwise secured in a slot in the upper portion of the barrel. To provide pressure 55 upon the pyrophoric element 23, the lever 25 is shown as pivoted at 27 and as provided

with a downwardly extending hooked finger 29. A coiled spring 28 is anchored to the finger 29. The spring 28 is shown as anchored at its remaining end to a pin 30 extending across the interior of the sliding trough or member 31 mounted for reciprocation within the barrel 18 and partly on the upper edge of the fore-hand portion of the stock 10.

To produce sparks by friction against the pyrophoric element a roughened or abradant member, as for instance, a piece of file 32, is shown as mounted adjacent the front end of the reciprocating trough 31. The trough 31 may be pulled by the hand of the user engaging a hammer member or button 12 carried by a rod 33, secured at 34 to the rear end of the reciprocating member 31 as by soldering or by means of a pin 35 or both, the walls of the reciprocating member 31 being shown as turned about the portion to enclose the same.

To hold the reciprocating member in retracted position and to permit of its sudden 50 release by pressure upon the trigger 14, there is shown a notch 36 provided by cutting away the lower side of the wall of the member 31, which notch is adapted to coact with the notch 37 in the trigger 14. The trigger may be pressed upwardly by the 55 coil spring 38 seated in a cavity 39 in the stock and surrounding the projection 40 formed upon the trigger, the trigger being pivoted at 41 upon a pin fastened through the stock at this point. The rod 33 is shown as passing through a bushing 42 in its reciprocating movement. The single spring 28 may be utilized to pull upon the reciprocating member 31 so as to produce the 60 relative movement between the friction member 32 and the pyrophoric element 23, and to provide pressure upon the lever 25 to press the pyrophoric element 23 against the friction element. The button 12 is shown 65 as provided with a notch at 43 which takes over the stock 10. The walls of the barrel 18 opposite the location where the sparks are produced are shown as perforated to allow the sparks to be the more readily 70 visible to the observer.

A finger piece 44 may be provided by the bent over lug carried by the lever 25 to assist in grasping the lever to lift the same out of the receptacle 24 against the pressure of the spring 28 when 75 it is necessary to renew the pyrophoric element 23. The lever 24 and the sparking 80

element receptacle are utilized to represent the front sight upon the barrel.

The operation of the invention will appear from the above description. Minor changes may be made in the physical embodiment of the invention without departing from its spirit.

I claim:

1. A toy gun comprising, in combination, 10 a tubular barrel, a reciprocating member within the barrel and having a portion protruding from the rear thereof adapted to be grasped by the hand of the user for retraction of said member, a spring in the barrel urging said reciprocating member forwardly to normal position, a trigger for holding the reciprocating member retracted and for sudden release of the same, a fric-

tion element mounted upon said reciprocating member, a pyrophoric element slidably mounted in the wall of said barrel, means for pressing said pyrophoric element against said friction element actuated by said spring.

2. A toy gun having a barrel, a retractile 25 slideable member within the barrel, a movable member on the barrel, said members having coating means to illuminate the muzzle of the barrel through sliding movement of the retractile member, a single means serving dually to normally urge sliding movement 30 of the retractile member and movement of the second mentioned member to effect more intimate engagement of the said coating means.

LOUIS V. ARONSON.
